UNITED STATES PATENT OFFICE.

LUDWIG VON SÜSSKIND, OF ST. GEORGEN, NEAR ST. GALLEN, SWITZERLAND.

PROCESS OF DRYING GOODS.

965,251.

Specification of Letters Patent. Patented July 26, 1910.

Application filed April 24, 1908. Serial No. 429,033.

To all whom it may concern:

Be it known that I, LUDWIG VON SÜSSKIND, a subject of the German Emperor, and resident of St. Georgen, near St. Gallen, 5 Switzerland, have invented a certain new and useful Improvement in Processes of Drying Goods, of which the following is a specification.

This invention relates to a process of drying substances, especially macaroni. In this 10 process air compressed by means hereinafter described is passed backward and forward through the macaroni or the like carried on a truck. According to the invention the 15 volume of air compressed is divided into two streams determined by the degree of dryness required, one stream being passed through a closed chamber in which the truck is located, and the other stream being passed 20 through a conduit provided with a regulating device, the adjustment of which determines the relative proportions of the fractions of the divided volume of air.

The drawings show a suitable apparatus 25 for performing the process.

Figure 1 is a longitudinal section of the 30 apparatus on the line A—B of Fig. 2, Fig. 2 is a vertical section on the line C—D of Fig. 1; Fig. 3 is a plan. Fig. 4 is a front view and Fig. 5 a plan of the crank and the adjustable crank pin.

As shown a piston *b* moves in the chamber *a*. The piston rod *c* rests on rollers *d* and on a guide rod *f* by means of a roller *e*; 35 this piston rod is further connected by a connecting rod *g* with a crank shaft *h* having an adjustable crank pin *h'* (Figs. 4 and 5) and driven in the usual manner. The chamber *a* is inclosed in a large chamber *k* 40 having side doors *i* and rails *l* for the truck *m* to be moved in and out, this chamber *k* being of such a width that two chambers *n* remain on either side when the truck is inside, these chambers *n* being connected with 45 one another by an overhead conduit *o* provided with a valve *p*. In the conduit *o* are placed two water vessels *q* for regulating the degree of moisture.

r indicates a manometer, *x* a thermometer and *s* a hygrometer.

Heating bodies *t* and *u* serve to regulate the temperature of the compressed air.

The apparatus is further provided with two fresh air suction valves *v* and two moist air outlet valves *w*.

When the crank shaft is driven, the piston moves to and fro and compressed air is produced on the one side of the piston and a vacuum on the other side. According to the adjustment of the valve *p* the whole of the 55 air current or only part of the same passes through the goods, the other part of the air current passes through the conduit *o* from the pressure side of the piston to its suction side.

Having now described my invention what I claim and desire to secure by Letters Patent of the United States is—

1. The herein described process of drying moist substances consisting in compressing 70 air in a closed chamber containing the substance to be dried, dividing the volume of compressed air into two streams according to the degree of dryness required, causing one stream to pass through the substance to 75 be dried and causing the other stream to follow a parallel path out of contact with said substance.

2. The herein described process of drying moist substances consisting in compressing 80 air in a closed chamber containing the substance to be dried, dividing the volume of air into two streams according to the degree of dryness required, causing one stream to pass through the substance to be dried and 85 causing the other stream to follow a parallel path and to overcome an adjustable resistance, regulating the temperature and dryness of the second stream, and reuniting the said streams.

3. The herein described process of drying moist substances, consisting in compressing a volume of air in a closed chamber containing the substance to be dried, causing one fraction of the volume of compressed air to 95 overcome the resistance presented by the substance and to pass through said substance, and causing the other fraction to overcome a regulatable resistance and to follow a parallel path on the outside of the 100 chamber.

4. The herein described process of drying moist substances consisting in passing a stream of air backward and forward in a

circuit including the substance to be dried, passing a second stream of air through a parallel circuit including a regulatable resistance while controlling the degree of dryness and temperature of the air, and reuniting the streams after their passage through the respective circuits.

In testimony whereof, I have signed my name to this specification in the presence of two subscribing witnesses.

LUDWIG VON SÜSSKIND.
